UNITED STATES PATENT OFFICE.

EDGAR B. WOLFE, OF NEWARK, NEW JERSEY, ASSIGNOR TO THE ELECTRIC MOTOR & EQUIPMENT COMPANY, A CORPORATION OF NEW JERSEY.

SIGN.

No. 882,857.

Specification of Letters Patent. Patented March 24, 1908.

Application filed September 21, 1907. Serial No. 393,899.

To all whom it may concern:

Be it known that I, EDGAR B. WOLFE, a citizen of the United States, residing at Newark, in the county of Essex and State of New Jersey, have invented certain new and useful Improvements in Signs; and I do hereby declare the following to be a full, clear, and exact description of the invention, such as will enable others skilled in the art to 5 which it appertains to make and use the same, reference being had to the accompanying drawings, and to characters of reference marked thereon, which form a part of this specification.

10 This invention relates, generally, to that class of inventions known in the art as illuminated or electric signs; and, the present invention has reference, more particularly to a novel construction of sign, substantially as 15 hereinafter more fully set forth, and a novel means for securing the letter-plates in position upon one or both sides of the sign-frame, providing a simple means for more easily and quickly securing said letter-plates in their 20 respective positions, and also to readily remove one or more of said plates when necessary.

25 This invention, therefore, has for its principal object to provide a novel and simply constructed sign and frame-work or support for the letter-plates, and a novel means for more readily securing each letter-plate in its position, than is at present the case.

Other objects of the present invention not 30 at this time more particularly enumerated will be clearly evident from the following description of the same.

With the various objects of my present invention in view, the said invention consists 35 primarily in the novel construction of sign hereinafter set forth; and, furthermore, the invention consists in the various arrangements and combinations of the devices and parts, as well as in the details of the construction of the same, all of which will be 40 more fully described in the following specification, and then finally embodied in the clauses of the claims, which are appended to and which form an essential part of this 45 specification.

50 The invention is clearly illustrated in the accompanying drawings, in which:

Figure 1 is a face view of the one side of a sign made according to and embodying the

principles of this invention; and Fig. 2 is a 55 similar view of the same, with the letter-plates upon the one side of the sign-frame shown removed. Fig. 3 is a horizontal section of the sign, the letter-plates upon the one side of the frame shown removed, said 60 view illustrating more particularly the inner construction of the sign-frame, and a series of finding-means or devices for securing each individual letter-plate in position. Fig. 4 is a transverse vertical section, taken on line 65 4—4 in said Fig. 2, looking in the direction of the arrow x; and Fig. 5 is a similar section, taken on line 5—5 in said Fig. 2, looking in the same direction. Fig. 6 is a detail rear view, on an enlarged scale, of the lower portion of a letter-plate and lower portion of the sign-frame, part of which is represented in section, and a rear-face view of one of the finding means or devices for securing the letter-plate in position; and Fig. 7 is a vertical section of the same, said section being taken on line 70 7—7 in said Fig. 6. Fig. 8 is a detail rear view, on an enlarged scale, of the upper portion of a letter-plate and upper portion of the sign-frame, part of which is 75 represented in section, and a rear face-view of one of a series of pivoted clamping means or devices for securing the letter-plate in position; and Fig. 9 is a vertical section of the same, said section being taken on line 80 8—8 in said Fig. 8.

Similar characters of reference are employed in all of the above described views, to indicate corresponding parts.

Referring now to the several figures of the 90 drawings, the reference-character 1 indicates the complete sign, and 2 is a rectangular or other suitably shaped frame-body or element, preferably made of sheet-metal, but which may be constructed of wood or other suitable 95 material, as will be clearly evident.

The frame-body or element, shown in the accompanying drawings, comprises the closed end-pieces 3 and 4, the closed top-piece 5 and closed bottom-piece 6, and the 100 open front 7 and open rear 8, said open front and rear being surrounded by inwardly extending marginal flanges 9, substantially as illustrated in the several figures of the drawings. Wrought or other suitably formed reinforcing braces 10 and 11, are arranged upon 105 the inner faces of the end-pieces 3 and 4 and the top-piece 5 and bottom-piece 6, said

braces being preferably made L-shaped in cross-section, and being secured in place by means of screws or bolts 12 and nuts 13. Angle-irons or plates 14 may also be secured 5 in the corners formed by said braces 10 and 11, said angle-irons or plates being secured in place by means of screws or bolts 15 and nuts 16. If desired, cross-stays or rods, as 17, may extend from one brace 11 to the other 10 brace 11, across the interior of the frame which is thus provided, said cross-stays being secured at their ends to the respective braces 11 by means of screws or bolts 18 and nuts 19.

The reference-character 20 indicates suitably formed face-plates, at the ends of the two faces of the said frame, and the reference-character 21 represents any suitable number of letter-plates, the said face-plates and letter-plates having their vertical edge-20 portions made to overlap, substantially as shown, and being detachably secured against the marginal flanges 9 by means of the fastening means or devices of the construction to be presently more fully described.

Each letter-plate 21 is provided upon its face with a suitably formed character 22, such as a letter, a number, monogram, or the like, and is provided with the usual holes or 25 openings 23, for the reception of the usual incandescent lamps, or lamp-sockets or receptacles, said lamps, or sockets or receptacles, however, not being shown in the accompanying drawings, because they are well-known, and may be of any suitable construction.

Referring now more particularly to Figs. 2, 4, 5, 8 and 9 of the drawings, I have shown therein, one form of a series of fastening means or clamping devices for securing the 40 upper portion of said end face-plates 20 and the letter-plates 21 over the open faces of the sign-frame, so that their upper edges will be clamped against the flanges 9, in the manner illustrated more particularly in Figs. 4, 5 and 45 9 of the drawings. As shown in said figures of the drawings, each fastening means or clamping device consists, essentially, of a short plate or bar-like element 24 which is provided in its upper portion with a screw-threaded hole 25 for the screwing therein of the screw-threaded shank of a screw 26. The upper edge-portions of said face-plates and letter-plates being arranged upon the outer face of the flanges 9, and the upper and 50 short end-portions of said plates or bar-like elements 24 being arranged against the inner face of the flanges 9, the screws 26 are inserted through suitably disposed holes 27 in said face or letter-plates, the screw-threaded shank of said screws being screwed in the oppositely located screw-holes 25 of the plates or elements, whereby, when the screws 26 are tightly screwed home, the parts will be 55 firmly and securely clamped in their assembled relations, as will be clearly evident.

By referring to Figs. 2, 4, 5, 6 and 7 of the drawings, it will be seen that the lower edge-portions of said end face-plates 20 and the letter-plates 21 may be secured over the open faces of the sign-frame, and against the flanges 9, by means of slidably arranged binding means or clamping devices. As shown in said figures of the drawings, each binding means or device consists, essentially, of a short plate or bar-like element 28 upon the face of which 70 is arranged a retaining plate 29 of sheet metal, or other suitable material. Said retaining plate 29 has its upper edge-portion bent or formed in a manner, so as to provide a holding member 32, which is fitted over and embraces the upper edge-portion of the plate or bar-like element 28, being suitably secured in place, preferably, by means of a rivet 31, or other suitable fastening means. The lower end-portion of said retaining plate 29, which 75 preferably extends slightly away from the lower part of said element 28, is bent or formed in such a manner, so as to provide a holding member 30 for the support therein of the lower edge-portions of the end face-plates 80 and the letter-plates, as will be clearly understood from an inspection of the drawings. Each plate or bar-like element 28 is provided in its lower portion with a screw-threaded hole 33, which is preferably made tapering, 85 as at 34, so as to provide an enlarged open end, and each retaining plate 29 is formed with a correspondingly located hole or opening 35 for the insertion therein of the screw-threaded shank of a screw 36. The lower 90 portions of said plates or bar-like elements 28 and the lower portions of said retaining plates 29 being arranged upon the opposite faces of the flange 9, with the lower marginal edge-portions of the face-plates and the letter-plates resting in the holding members 30, the screws 36 are inserted through suitably disposed holes 37 in said face or letter-plates, the screws being inserted through the holes or openings 35 and screwed into the screw-threaded holes 33 of the plates or bar-like elements 28, whereby, when the screws are 95 tightly screwed home, the parts will be firmly and securely clamped in their assembled relations, as will be clearly evident from an inspection of said Fig. 7 of the drawings.

Having thus described the general construction of the sign, I will now briefly set forth the manner of securing the face-plates and letter-plates in their respective positions 100 upon one or both sides of the sign-frame, according as to whether the sign is to be used as a wall-sign, or is to extend at an angle, usually at right angles, from the wall. The first step in the operation is usually to loosely fasten the upper portions of the face-plates and letter-plates to the frame by means of the fastening or clamping devices 24, the loose angular and outwardly swinging relation of the plates 20 and 21 permitting the 105 110 115 120 125 130

operator to place one arm and his hand back of the plates, so as to guide the plate or bar-like elements 24 against the ends of the screws 26, whereby the screws can be screwed into place, and the parts loosely assembled. 5 This loose arrangement of the end face-plates and letter-plates permits the operator to arrange the finding means or clamping device, which comprises the plates or elements 28 10 and retaining plates 29, in the relative positions indicated in said Fig. 7, and by laterally sliding each device from right to left, or vice versa, by taking hold of holding members 30, the holes 33 and 35 can be brought 15 directly back of the holes 37 in the end face-plates or letter-plates, thus enabling a quick and easy insertion of the ends of the screws 36 through the holes 37 and 35, and into the enlarged or tapered portions 34, so as to be 20 tightly screwed into the screw-holes 33. All the screws 26 and 36 can then be tightly screwed home, so as to firmly secure the several face-plates and the letter-plates in position, and the sign is ready for use.

25 From the foregoing description of my present invention it will be clearly seen, that I have produced a simple sign-construction, which enables the various face-plates and letter-plates to be secured in position, or to be 30 removed from the sign-frame to make necessary changes or repairs, or to slightly loosen the plates, when it is necessary to get at the circuit-wires contained within the frame.

Of course it will be evident, that various 35 changes may be made in the arrangements and combinations of the various devices and parts, as well as in the details of the construction of the said parts, without departing from the scope of my present invention, as 40 defined in the appended claims. Hence, I do not limit my invention to the exact arrangements and combinations of the devices and parts thereof, as described in the foregoing specification and as illustrated in the 45 accompanying drawings, nor do I confine myself to the exact details of the construction of any of the said parts, except as defined by the scope of said claims.

I claim:—

50 1. In a sign, the combination with an open-faced frame, of a series of face and letter plates adapted to be arranged over the open face of the frame, and slid able fastening devices for securing said plates in position, each fastening device comprising a plate-like element, and a retaining plate upon one face of said plate-like element, a holding member 55 connected with said retaining plate for securing the edge-portion of said face and letter-plates to said fastening devices, and means for securing said fastening devices in fixed positions.

2. In a sign, the combination with an open-faced frame, of a series of face and letter plates adapted to be arranged over the

open face of the frame, and slid able fastening devices for securing said plates in position, each fastening device comprising a plate-like element, and a retaining plate upon one face of said plate-like element, a holding member 70 connected with said retaining plate for securing the edge-portion of said face and letter-plates to said fastening devices, said plate-like elements, retaining-plates and said face and letter-plates being provided with 75 screw-receiving holes, and screws for securing said fastening devices in fixed positions.

3. In a sign, the combination with an open-faced frame, of a series of face and letter plates adapted to be arranged over the 80 open face of the frame, and slid able fastening devices for securing said plates in position, each fastening device comprising a plate-like element, and a retaining plate upon one face of said plate-like element, a 85 holding member connected with said retaining plate for securing the edge-portion of said face and letter-plates to said fastening devices, said plate-like elements being provided with screw-threaded holes formed with 90 enlarged open portions providing finding means, said retaining-plates and said face and letter-plates being provided with correspondingly disposed openings, and screws for securing said fastening devices in fixed positions. 95

4. In a sign, the combination with an open-faced frame, of a series of face and letter plates adapted to be arranged over the open face of the frame, and slid able fastening 100 devices for securing said plates in position, each fastening device comprising a plate-like element, a retaining plate upon one face of said plate-like element, a holding member upon the upper portion of said retaining 105 plate fitted over the upper edge of the plate-like element, a second holding member at the lower portion of said retaining plate for securing the edge-portion of said face and letter-plates to said fastening devices, and 110 means for securing said fastening devices in fixed positions.

5. In a sign, the combination with an open-faced frame, of a series of face and letter plates adapted to be arranged over the open face of the frame, and slid able fastening devices for securing said plates in position, each fastening device comprising a plate-like element, a retaining plate upon one face of said plate-like element, a holding member 120 upon the upper portion of said retaining plate fitted over the upper edge of the plate-like element, a second holding member at the lower portion of said retaining plate for securing the edge-portion of said face and letter-plates to said fastening devices, said plate-like elements, retaining-plates and said face and letter-plates being provided with screw-receiving holes, and screws for securing 125 said fastening devices in fixed positions. 130

6. In a sign, the combination with an open-faced frame, of a series of face and letter-plates adapted to be arranged over the open face of the frame, and slidable fastening devices for securing said plates in position, each fastening device comprising a plate-like element, a retaining plate upon one face of said plate-like element, a holding member upon the upper portion of said retaining plate fitted over the upper edge of the plate-like element, a second holding member at the lower portion of said retaining plate for securing the edge-portion of said face and letter-plates to said fastening devices, said plate-like elements being provided with screw-threaded holes formed with enlarged open portions providing finding means, said retaining-plates and said face and letter-plates being provided with correspondingly disposed openings, and screws for securing said fastening devices in fixed positions.

7. In a sign, the combination with an open-faced frame, surrounded by a marginal flange, of a series of plates adapted to be arranged over the open face of the frame and upon the flange, fastening devices consisting of plate-like elements 24, said plate-like elements and said plates being provided with screw-receiving holes, and screws for securing the upper edge-portions of said plates to said flange, and slidable fastening devices for securing the lower edge-portions of said plates to said flange, and means for securing said slidable fastening devices in fixed positions.

8. In a sign, the combination with an open-faced frame, surrounded by a marginal flange, of a series of plates adapted to be arranged over the open face of the frame and upon the flange, fastening devices consisting of plate-like elements 24, said plate-like elements and said plates being provided with screw-receiving holes, and screws for securing the upper edge-portions of said plates to said flange, and slidable fastening devices for securing the lower edge-portions of said plates to said flange, said slidable fastening devices and said plates being provided with screw-receiving holes, and screws for securing said slidable fastening devices in fixed positions.

9. In a sign, the combination, with an open-faced frame, surrounded by a marginal flange, of a series of face- and letter-plates adapted to be arranged over the open face of the frame and upon the flange, fastening devices consisting of plate-like elements 24, said plate-like elements and said face and letter-plates being provided with screw-receiving holes, and screws for securing the upper edge-portions of said plates to said flange, and slidable fastening devices for securing the lower edge-portions of said face and letter-plates upon said flange, each slid-able fastening device comprising a plate-like

element, and a retaining plate upon one face of said plate-like element, a holding member connected with said retaining plate for securing the lower edge-portions of said face and letter-plates to said slidable fastening devices, and means for securing said slidable fastening devices in fixed positions.

10. In a sign, the combination, with an open-faced frame, surrounded by a marginal flange, of a series of face- and letter-plates adapted to be arranged over the open face of the frame and upon the flange, fastening devices consisting of plate-like elements 24, said plate-like elements and said face and letter-plates being provided with screw-receiving holes, and screws for securing the upper edge-portions of said plates to said flange, and slidable fastening devices for securing the lower edge-portions of said face and letter-plates upon said flange, each slid-able fastening device comprising a plate-like element, and a retaining plate upon one face of said plate-like element, a holding member connected with said retaining plate for securing the lower edge-portions of said face and letter-plates to said slidable fastening devices, said plate-like elements, retaining plates and lower portions of said face and letter-plates being provided with screw-receiving holes, and screws for securing said slidable fastening devices in fixed positions.

11. In a sign, the combination, with an open-faced frame, surrounded by a marginal flange, of a series of face- and letter-plates adapted to be arranged over the open face of the frame and upon the flange, fastening devices consisting of plate-like elements 24, said plate-like elements and said face and letter-plates being provided with screw-receiving holes, and screws for securing the upper edge-portions of said plates to said flange, and slidable fastening devices for securing the lower edge-portions of said face and letter-plates upon said flange, each slid-able fastening device comprising a plate-like element, and a retaining plate upon one face of said plate-like element, a holding member connected with said retaining plate for securing the lower edge-portions of said face and letter-plates to said slidable fastening devices, said plate-like elements being provided with screw-threaded holes formed with enlarged open portions providing finding means, said retaining plates and the lower portions of said face and letter-plates being provided with correspondingly disposed openings, and screws for securing said slidable fastening devices in fixed positions.

12. In a sign, the combination, with an open-faced frame, surrounded by a marginal flange, of a series of face- and letter-plates adapted to be arranged over the open face of the frame and upon the flange, fastening devices consisting of plate-like elements 24, said plate-like elements and said face and

- letter-plates being provided with screw-receiving holes, and screws for securing the upper edge-portions of said plates to said flange, and slidable fastening devices for securing 5 the lower edge-portions of said face and letter-plates upon said flange, each slidable fastening device comprising a plate-like element, and a retaining plate upon one face of said plate-like element, a holding member upon 10 the upper portion of said retaining plate fitted over the upper edge of the plate-like element, a second holding member at the lower portion of said retaining plate for securing the lower edge-portions of said face 15 and letter-plates to said slidable fastening devices, and means for securing said slidable fastening devices in fixed positions.
13. In a sign, the combination, with an open-faced frame, surrounded by a marginal flange, of a series of face- and letter-plates 20 adapted to be arranged over the open face of the frame and upon the flange, fastening devices consisting of plate-like elements 24, said plate-like elements and said face and 25 letter plates being provided with screw-receiving holes, and screws for securing the upper edge-portions of said plates to said flange, and slidable fastening devices for securing the lower edge-portions of said face 30 and letter-plates upon said flange, each slid- able fastening device comprising a plate-like element, and a retaining plate upon one face of said plate-like element, a holding member upon the upper portion of said retaining 35 plate fitted over the upper edge of the plate-like element, a second holding member at the lower portion of said retaining plate for securing the lower edge-portions of said face and letter-plates to said slidable fastening 40 devices, said plate-like elements, retaining plates, and lower portions of said face and letter-plates being provided with screw-receiving holes, and screws for securing said slidable fastening devices in fixed positions.
- 45 14. In a sign, the combination, with an open-faced frame, surrounded by a marginal flange, of a series of face- and letter-plates 50 adapted to be arranged over the open face of the frame and upon the flange, fastening devices consisting of plate-like elements 24, said plate-like elements and said face and letter-plates being provided with screw-receiving holes, and screws for securing the upper edge-portions of said plates to said 55 flange, and slidable fastening devices for securing the lower edge-portions of said face and letter-plates upon said flange, each slid- able fastening device comprising a plate-like element, and a retaining plate upon one face 60 of said plate-like element, a holding member upon the upper portion of said retaining plate fitted over the upper edge of the plate-like element, a second holding member at the lower portion of said retaining plate for se-
- curing the lower edge-portion of said face and 65 letter-plates to said slidable fastening devices, said plate-like elements being provided with screw-threaded holes formed with enlarged open portions providing finding means, said retaining plates and the lower portions of 70 said face and letter-plates being provided with correspondingly disposed openings, and screws for securing said slidable fastening devices in fixed positions.
15. In a sign, the combination with an 75 open-faced frame, surrounded by a marginal flange, of a series of face and letter-plates, said plates being provided with screw-receiving holes, and said plates being adapted to be arranged over the open face of said frame and 80 upon said flange, and fastening devices consisting of plate-like elements 24, each plate-like element being provided with a screw-threaded hole located nearer to one end of said element than to its other end, so that 85 said plate-like elements before being tightly screwed in their fixed positions will hang vertically, substantially as and for the purposes set forth.
16. The herein described fastening device 90 consisting of a plate-like element and a retaining plate arranged upon the face of said element, the lower end-portion of said retaining plate being bent-over to provide a holding portion, said retaining plate being pro- 95 vided with a screw-receiving opening, and said plate-like element being provided with a screw-threaded hole formed with an enlarged open portion which registers with the opening in said retaining plate, substantially as 100 and for the purposes set forth.
17. The herein described fastening device 105 consisting of a plate-like element and a retaining plate arranged upon the face of said element, the lower end-portion of said retaining plate being bent-over to provide a holding portion, and said retaining plate being provided upon its upper portion with a bent-over part forming a holding portion which 110 embraces the upper edge of said plate-like element, said retaining plate being provided with a screw-receiving opening, and said plate-like element being provided with a screw-threaded hole formed with an enlarged open portion which registers with the opening in said retaining plate, substantially as 115 and for the purposes set forth.
18. A sign comprising an open-faced frame, made of sheet-metal, and reinforcing braces 120 10 and 11 arranged and secured upon the inner faces of the end-pieces, and the top and bottom pieces of said frame, and angle-irons secured in the corners formed by said braces, substantially as and for the purposes set forth.
19. A sign comprising an open-faced frame, made of sheet-metal, and reinforcing braces 125 10 and 11 arranged and secured upon the

inner faces of the end-pieces, and the top and bottom pieces of said frame, and angle-irons secured in the corners formed by said braces, and cross-stays extending from brace to brace across the interior of said frame, substantially as and for the purposes set forth.

In testimony, that I claim the invention set

forth above I have hereunto set my hand this 19th day of September, 1907.

EDGAR B. WOLFE.
